PULSE GENERATOR

Donald D. Grieg, Forest Hills, N. Y., assignor to
Federal Telephone and Radio Corporation,
New York, N. Y., a corporation of Delaware

Application December 20, 1943, Serial No. 514,999

8 Claims. (Cl. 250—27)

1

This invention relates to pulse generating systems particularly useful in radio and other electrical circuits.

In my copending application, Serial No. 511,406, now Patent Number 2,434,920, filed November 23, 1943, I disclose a system for producing from input pulses or waves of any given shape a wave of substantially a given amplitude characteristic for any desired frequency within a given wide band of frequencies and/or a rectangular pulse of any desired width within wide limits. This is accomplished by first generating an "edger pulse" from the input pulse, the edger pulse being of a pulse form having one edge, either leading or trailing, which is substantially vertical while the other opposite edge is curved gradually, preferably in an exponential manner, in its build-up or decay. The edger pulse thus obtained is then used to shock excite a resonant circuit in conjunction with a damping means for producing damped waves of substantially a given amplitude characteristic for any desired frequency within a given wide band of frequencies or for producing pulses of any desired width within wide limits, the selection of frequency of pulse width being accomplished by controlling the tuning of the resonant circuit.

One of the objects of this invention is to provide a further method and means for producing an edger pulse from a substantially rectangular input pulse.

Another object of my invention is to produce, from substantially rectangular input pulses, saw-tooth pulses wherein the sharpness of the saw-tooth points is independent of the width of the input pulses.

A further object of the invention is to provide a method and means for producing edger or saw-tooth pulses retarded with respect to the input pulse.

The above and other objects of the invention will become apparent from a consideration of the following detailed description to be read in connection with the accompanying drawings, in which:

Fig. 1 is a schematic wiring diagram with parts shown in block form of one embodiment of the edger pulse generator according to my invention;

Fig. 2 is a graphical illustration useful in explaining the operating features of the embodiment of Fig. 1;

Fig. 3 is a schematic wiring and block diagram of another embodiment of my invention;

Fig. 4 is a graphical illustration indicating the

operating and retardation features of the embodiment of Fig. 3; and

Fig. 5 is a schematic wiring and block diagram of still another embodiment of the invention.

5 In Fig. 1 the edger pulse generator is shown to comprise a saw-tooth generator circuit 10, a mixer 12 and a clipper 14. The saw-tooth generator is of known character having a vacuum tube 16 with a control grid 18 which is provided with a suitable negative bias through resistance 20. Connected across the plate and cathode electrodes of the tube 16 is a condenser 22. The plate is supplied from a source of positive current through load resistor 24.

10 The usual operation of the saw-tooth generator circuit is illustrated by curves *a* and *b* of Fig. 2. Curve *a* shows input pulses 26 which preferably are of rectangular shape. Curve *b* represents the output voltage across load resistor 24 as it appears 15 at the output connection 28. Assuming that the condenser 22 is fully charged as represented by the level 30 on curve *b*, the leading edge 26a of the input pulse will cause the tube 16 to conduct thereby discharging the condenser 22 as indicated by the slightly inclined edge 32. The current continues to flow for the duration of the pulse 26 as indicated by the flat end portion 34. When the trailing edge 26b of the input pulse occurs, the negative bias on the grid 18 blocks 20 further flow through the tube. The condenser then recharges as indicated by the exponential edge 36, the build-up of which is determined by the applied voltage, the resistance 24 and the capacity of condenser 22.

25 In the usual practice of generating saw-tooth waves, it is customary to narrow the input pulse as much as possible so as to eliminate the flat end portion 34. This, however, is exceedingly difficult to accomplish for even in the case where sharp pulses are produced by differentiating circuits there will exist some width even though very small.

30 In accordance with the principles of my invention, the flat end portion 34 is entirely eliminated and an edger pulse or sharp pointed saw-tooth is produced. One edge of the produced pulse is substantially vertical and the opposite edge is curved with the curved portion intersecting the vertical edge portion to form the top or end portion of the pulse. This is accomplished by applying the output of the saw-tooth generator 10 to the mixer circuit 12 of known character to which I also apply the input pulse voltage 26. The two voltages combine algebraically, since 35 they are of opposite polarity, to produce a dis-

torted pulse shape which is the algebraic sum of the two input voltages. The resulting shape for the mixed voltages of curves *a* and *b* is shown in curve *c*. Since the leading edge 32 of the saw-tooth is inclined, the mixing of the two voltages cancels out the overlapping portions thereof leaving those portions of the two voltages which are not overlapped by the other voltage. Thus, the leading edge portion of the input pulse occurring ahead of the saw-tooth produces a sharp positive pulse portion 40 while the trailing edge portion of the saw-tooth which extends beyond the trailing edge 26b of the input pulse produces a negative edger pulse portion 42. By a clipping operation at the zero axis of the energy of curve *c* the edger pulse portion 42 is obtained as indicated by curve *d*, the vertical leading edge portion 42a corresponding to the vertical trailing edge 26b of the input pulse and the trailing edge 42b being curved exponentially like the trailing edge 36 of the saw-tooth.

If saw-teeth are desired, the clipping level may be lowered from the zero axis as indicated by level 45 whereby saw-teeth 46 (curve *e*) having substantially linearly sloping trailing edges are obtainable.

In Fig. 3 I show a second embodiment of the invention whereby both positive and negative edger pulses are produced. This circuit includes a resistance-capacitance circuit to which input pulses 50, curve *f*, Fig. 4, are applied. The circuit includes a resistor *R* connected in series with a condenser *C* to ground. The output 52 of this circuit is taken off at the interconnection between elements *R* and *C*. The RC values of this circuit alter the shape of the rectangular input pulse substantially as indicated at 54, curve *g*. It will be understood, of course, that the curved edges of the shaped pulse 54 may be varied according to the relative values of the elements *R* and *C*. It will be readily apparent, however, that for the duration of the input pulse 50, the circuit values may be such as to provide a condenser charging rate as indicated by the leading edge 54a, and a discharge rate as indicated by the curved trailing edge 54b.

The input pulses are also applied to a phase reverser 60 whereby they are reversed in polarity as indicated at 61, curve *h*. The output connections 52 and 62 of the RC circuit and the phase reverser 60 may be applied to any known mixer circuit 64 wherein the two pulse energies 54 and 61 are added algebraically to produce an output wave 65, curve *i* having two edger pulse portions. The first edger pulse portion is negative and is defined by a vertical edge 65a which corresponds to the vertical edge 61a of the rectangular pulse 61 and a curved trailing edge 65b which corresponds to the curved leading edge 54a. The second edger pulse portion is positive and is defined by a vertical edge 65c which corresponds to the vertical trailing edge 61b of the rectangular pulse 61 and a curved trailing edge 65d which corresponds to the curved edge portion 54b.

The mixer 64 may comprise, for example, a known hybrid coil for mixing the two pulse energies, or a known T-pad resistor network may be used. Mixers of this character may be used where elimination of vacuum tubes is important. The transformer and resistor types of mixers, however, have the disadvantage of distorting somewhat the frequency and shape of the pulse waves. Such distortion, however, can be kept small and therefore may be tolerated in many applications of the invention.

Either of the two edger pulse portions 65a-b or 65c-d is obtainable by a clipping operation performed by a known clipper 70 having a clipper tube and a phase reverser tube with output connections 71 and 72 with respect to a ground connection 73, whereby the positive pulse portion 65c-d is obtainable on output connection 71 and negative pulse portions 65a-b are obtained from output connection 72 by the required clipping operation.

It will be observed that the negative pulse portion 65a-b has the vertical leading edge thereof in coincidence with the leading edge of the rectangular input pulse 50, and that the leading edge 65c of the positive pulse portion is in coincidence with the trailing edge of the input pulse 50. Thus, the positive edger pulse 65c-d is actually retarded an amount corresponding to the width of the input pulse with respect to the leading edge of the input pulse. Any retardation desired for an output edger pulse may be obtained by extending, by means of a multivibrator or other rectangular pulse generating circuit, the input pulse a width equal to the desired retardation effects desired.

It will be understood, also, that either of the output edger pulses may be reversed by applying the same to a phase reverser or, if desired, the input pulse 50 may be reversed from positive to negative polarity prior to its application to the circuit. This would have the effect of reversing the polarity of the pulses of curves *j* and *k*.

In Fig. 5 I show a third embodiment which is similar to the embodiment shown in Fig. 3 except that the mixer unit 64a comprises two vacuum tubes 81 and 82. The RC output connection 52 is applied to the grid of tube 81. In order to provide a grid leak which will not short-circuit the condenser *C*, I connect the input connection 51 through a resistor 83 to ground. The output connection 62 of phase reverser 60 is connected to the grid of the tube 82. The plate connections 86 and 87 of the two tubes 81 and 82, respectively, are supplied with plate current through load resistor 90. The output connection 92 for the mixer unit is connected to the clipper circuit 70.

The two tube feature of the mixer unit provides separate cathode biasing means 81a and 82a, whereby each tube can be biased according to the character of input energy. For the pulse energies shown, tube 81 is provided with a greater negative bias than tube 82.

In operation, the positive input pulse 50 produces a shaped pulse 54 similarly as in the circuit of Fig. 3. Likewise, phase reverser 60 reverses the input pulse 50 as shown at 61 prior to its application to the mixer. The tube 81 reverses the polarity of the shaped pulse 54 as shown at 84. Likewise, the pulse 61 is reversed in polarity by tube 82 as shown at 85. The resulting pulse output across the load resistor 90 is shown at 95. It will be observed that due to the reversing functions of this circuit the positive pulse portion 95a occurs in time relation with the leading edge portion of the input pulse 50 and the negative pulse portion 95b is timed with the trailing edge portion of the input pulse 50. This is the reverse to the polarity output of the circuit of Fig. 3. The clipping operation of clipper 70 in Fig. 5 is the same as described for Fig. 3 whereby pulse portions 95a and 95b are separately obtainable from connection 71 and 72.

The tube mixer unit 64a of Fig. 5 is to be preferred over the hybrid coil or T-pad mixer ar-

rangements hereinbefore referred to for mixer 64 in Fig. 3. The tube mixer, for example, is free from any frequency or wave distortion that may be present in the simpler forms of mixer units.

While I have described above the principles of my invention in connection with specific apparatus, and particular modifications thereof, it is to be clearly understood that this description is made only by way of example and not as a limitation on the scope of my invention and the accompanying claims.

I claim:

1. The method of producing an edger pulse comprising producing from a rectangular input pulse a shaped pulse at least one edge of which is curved, mixing the energy of this shaped pulse with the input pulse energy in opposite polarity to said input pulse to produce a pulse portion one edge of which is substantially vertical according to one of the vertical edge portions of the input pulse, and the other opposite edge is curved according to said curved edge, said vertical edge portion being contiguous to said opposite curved edge.

2. The method defined in claim 1 wherein the produced shaped pulse is of a generally saw-tooth shape having a flat end portion which approaches in width the width of the input pulse, whereby the mixing operation subtracts from the saw-tooth shaped pulse the portion thereof which includes said flat end portion.

3. The method defined in claim 1 wherein the produced shaped pulse is of a shape having curved leading and trailing edges, whereby the mixing of the input pulse therewith operates to produce two pulse portions one pulse portion being defined by the vertical leading edge of the input pulse and said curved leading edge and the other pulse portion being defined by the vertical trailing edge of said input pulse and said curved trailing edge.

4. A system for producing edger pulses from substantially rectangular pulses comprising means for producing in response to a rectangular input pulse a shaped pulse at least one edge of which is curved, mixer means, means to apply energy of said shaped pulse to said mixer means, and means including a phase reverser to apply energy of said input pulse to said mixer means of opposite polarity to the polarity of said shaped pulse, whereby they combine algebraically to produce a pulse portion one edge of which is substantially vertical corresponding to one of the edges of said input pulse and the other edge of which is curved according to said one curved edge.

5. The system defined in claim 4 wherein the shaped pulse producing means comprises a condenser, a vacuum tube having an input grid, a plate electrode and a cathode electrode, means to supply the plate electrode with current to charge said condenser, whereby energy of an input pulse causes said tube to conduct and to rapidly discharge said condenser, and said grid

having means to bias the tube negatively so that, at the termination of said input pulse, said tube returns to cut-off permitting the condenser to recharge and thereby produce the curved edge for said shaped pulse.

6. The system defined in claim 4 wherein the shaped pulse producing means includes a resistance-capacitance circuit of a time constant such that the leading edge portion of the input pulse is translated into a curved edge for substantially the duration of the input pulse and the trailing edge is extended in a curved exponential shape.

7. The system defined in claim 4 wherein the shaped pulse producing means includes a resistance-capacitance circuit of a time constant such that the leading edge portion of the input pulse is translated into a curved edge for substantially the duration of the input pulse and the trailing edge is extended in a curved exponential shape, and said mixer means includes vacuum tubes, one for each pulse energy input, whereby the shaped pulse energy and the rectangular pulse energy are inverted in polarity before they are mixed, the tube for receiving the shaped pulse energy having a grid leak resistor connected to the input of the resistance-capacitance circuit.

8. A system for producing from substantially rectangular pulses positive and negative edger pulses wherein one edge of each such pulse is

substantially vertical and the opposite edge is curved, comprising a resistance-capacitance circuit the time constants of which translates the leading edge of each rectangular input pulse into a curved edge for substantially the duration of the input pulse and translates the vertical trailing edge of the input pulse into a curved exponential edge, a mixer, a phase reverser, means for applying energy of each rectangular input pulse to said phase reverser, means for applying the output of said phase reverser to said mixer, means to apply the curved pulse output of said resistance-capacitance circuit to said mixer, whereby the reversed input pulse energy is combined algebraically with the curved pulse shape in opposite polarity to produce a negative pulse portion the leading edge of which corresponds to the leading edge of said rectangular input pulse and the trailing edge portion of which corresponds to the leading curved edge of said curved pulse, and a positive pulse portion the leading edge of which corresponds to the vertical trailing edge of said rectangular input pulse and the trailing edge of which corresponds to the curved trailing edge of said curved pulse, and clipper means for separating the two pulse portions.
